CONTAINER CARRIER

Elwyn R. Gooding, Ann Arbor, Mich., assignor to
Ex-Cell-O Corporation, Detroit, Mich.
Filed Apr. 2, 1965, Ser. No. 445,062
3 Claims. (Cl. 206—65)

ABSTRACT OF THE DISCLOSURE

A container carrier for packaging a plurality of cans wherein the carrier holding elements retain each can bead in a static interlocked relation with the carrier. The holding elements of the carrier are arranged to provide lead-in guides for the bead for machine application.

The present invention relates to a container carrier and more particularly to a container carrier for securing together a group of cylindrical containers of the type having a peripheral bead or rim on at least one end. At the present time it is common practice in the container packaging art to secure together, by means of a suitable carrier made from a plastic or like material, a group of containers or cans of beer, soft drinks or the like, into a package. The carriers function to retain the containers in a compact unit and to provide a carrying handle for the package. Heretofore, carriers of this type have been costly to manufacture, difficult to attach to the containers and unable to withstand rough treatment.

An object of the present invention is therefore the provision of an inexpensive container carrier for securing together a group of containers which is readily adapted to automatic feeding and attachment.

Another object is to provide a fastening device for the purpose described which securely retains the cans in assembled relation, yet is readily removable by the purchaser.

A further object of the invention is the provision of a carrier that can be constructed with a minimum amount of material by injection molding or thermo formed fabrication.

Still another object is to provide a carrier in which the containers are completely supported by the top portions alone.

A more specific object of the present invention is to provide a novel one-piece carrier member adapted to be applied to at least four adjacent containers in a manner, so that the carrier retains said containers due to the physical interlocking relationship of the carrier components to the container bead or rim.

A final object of the present invention is the provision of a container carrier for securing a plurality of containers together to form a multicarrier package that is adapted to be stacked on another similar package in substantially the same manner as the conventional carrier type packages may be stacked.

Other objectives and advantages of the invention will be apparent from the following detailed description and claims, taken in connection with the accompanying drawings which form part of the instant specification, and which are to be read in conjunction therewith and in which like reference numerals are used to indicate like parts in various views wherein:

FIG. 1 is a perspective view showing package including a plurality of cans disposed in side-by-side substantially abutting and parallel relationships and retained by a carrier incorporating features of the present invention;

FIG. 2 is a plan view of the package shown in FIG. 1;

FIG. 3 is a top plan enlarged view showing the carrier of the present invention;

FIG. 4 is a bottom plan enlarged view of the carrier shown in FIG. 3;

2

FIG. 5 is a side elevational view of the carrier of FIG. 4;

FIG. 6 is an elevational side view taken in the direction of the arrow 6 of FIG. 4;

FIG. 7 is an enlarged view in section taken on line 7—7 of FIG. 2;

FIG. 8 is a fragmentary sectional view showing the flange in rotated position providing clearance for the container bead taken on line 7—7 of FIG. 2; and

FIG. 9 is a perspective view showing a package incorporating a modified form of the carrier.

While the invention is susceptible of various modifications and alternative constructions, certain illustrative carriers have been shown in the drawings and will be described below in detail. It should be understood, however, that there is no intention to limit the invention to the specific forms disclosed. On the contrary, the intention is to cover all modifications, alternative constructions, equivalents and uses falling within the spirit and scope of the invention as expressed in the appended claims.

Referring more specifically to the drawings (FIG. 1) there is shown a package 10 which represents an illustrative embodiment of the present invention. The package comprises a group of six individual containers 12 disposed in side-by-side parallel relationships and held by a carrier 14. As can be seen from FIG. 2 the annular beads 16 of the containers are substantially abutting each other at the points indicated by the numeral 18. The beads 16 (FIG. 7) extend not only beyond the end 20 of the containers 12 but also beyond the periphery of the tubular body walls 22.

The "six pack" arrangement shown contains two interior open-ended spaces 24 and 26 which extend parallel to the axis of the containers. The carrier 14 consists of a pair of identical generally square shaped attaching units 28 and 30 symmetrically located in relation to the spaces 24 and 26. The individual unit 28 configuration is indicated by the dashed line 32 in FIG. 2. The units 28 and 30 are shown connected together at adjacent corners by web portion 34 to produce the one-piece carrier 14 of the package 10. While the package of FIG. 1 is shown in the familiar "six pack" arrangement it will be apparent that the carrier can be constructed for use with two-container and four-container packages as well as the six-container package shown. Also, by using a third attaching unit and forming it integrally in tandem arrangement, the six-container package of FIG. 1 can be increased to an eight-container package. Various other modifications of the invention may be employed depending upon the number of containers to be packaged or the method of package assembly to be employed.

The basic attachment units 28 and 30 include an upper square frame member 36 in the form of a generally horizontal planar body extending across the top of the containers 12. The frame 36 overlies the upper edge of the beads 16 of each container on one side of the area 18 of substantial abutment of the containers. As illustrated, each attachment unit is provided with a panel 38 which has a square configuration of predetermined size such that it will fit closely within the spaces 24, 26. The horizontal disposed panel 38 is located in vertically spaced relation to the frame 36 and rigidly secured thereto by means of corner posts or braces 40.

The frame 36 contains four arcuate guide tabs 42 on its underside planar surface 43 that are positioned and adapted to guide the beads 16 of the containers into their retained interlocked position shown in phantom lines (FIG. 4). The central portion of each tab 42 has a planar face 44 for retaining the bead 16 in its locked position in a manner to be described. It will be noted from FIG. 4 that the radius of the arcuate tabs 42 is somewhat less than the radius of the container beads so as not to con-

form to the curvature of the beads in order to provide a convergent lead-in guide channel 45 between the braces 40 and the convex surface portion of the tabs when the container is in its retained position.

As indicated in FIG. 7 the panel 38 is formed with an upstanding flange 46 whose upper horizontal edge surface 48 engages in supporting relation the underside 47 of the bead 16. The flange 46 is tapered outwardly at an angular relation of approximately 80° to the plane of the panel 38 so that it can be elastically pivoted to a substantially vertical position (FIG. 8) where it will provide sufficient clearance to allow downward movement of tab 42 to its location shown in FIG. 7. It will be noted that the sloped outer face of flange 46 does not bear against the container wall 22 in interlock position. The axial center of the panel 38 has formed therein an enlarged opening 49 providing a finger hole and the wall of the opening is preferably rolled over, as at 50, to avoid the forming of rough edges.

In order to allow entry of the bead 16 into its retained position (FIG. 7) it can be seen that the vertical distance measured from the undersurface 43 to the upward facing edge 49 must be greater than the height of the bead 16 as measured from its lower most portion 47 to its upper extremity 54. There is no applicable vertical separation of the surface 43 and 48 during container insertion can be seen from the particular construction of the units 28, 30 wherein the frame 36 and panel 38 members are formed respectively with continuous tabs 42 and flanges 46 which act as stiffening ribs to prevent appreciable horizontal deflection of the members.

Assembly of the carrier onto the containers can thus only be completed by forcing the deformable flange 46 inwardly to a substantially vertical position (FIG. 8) by pivoting about its point of juncture with panel 38. The flange 46 is deformed to a location so that the central flat portion 44 of tab 42 is free to move downwardly so as to be positioned below and inwardly of the bead 16. As best seen in FIG. 4, the bead 16 is slid or directed into channel 45, with the outer portion of the bead 16 riding on the arcuate extremity of tab 42 until the pivoting of flange 46 allows downward movement of the tab.

To permit the carrier 12 to be readily positioned in interlocked relation with the containers, the faces 44 of rigid tabs 42 can be formed so as to slope toward the beads 16, as best shown in FIGS. 3 and 7. The diagonal edge configuration 52 results from the intersection of the vertical arcuate surface of the tab 42 with the face 44. Due to the fact that the carrier of the instant invention is relatively rigid, it has been determined that the carrier can be more easily rolled onto the container bead by first having the bead enter the channel 45 and be guided into its interlocked position by the curved portion of the tabs. The result is that the diagonal edge 52 permits a point contact at 54 during the initial bead engagement with the retaining tab so as to permit the upper edge 48 of flange 46 to move into contact with the underside of bead 16.

Once the tab face 44 is positioned in place behind the bead 16, the flange 46 is free to pivotally return to its static or unstressed position shown in FIG. 7 wherein the container is held against downward movement by the positioning of horizontal edge 48 beneath the bead 16. The function of the tabs is to act as a physical static barrier to prevent outward horizontal movement of the container. Contact between the posts 40 and the outer portion of bead 16 limits horizontal movement of the container in the direction of flange 46. Thus, by applicant's novel arrangement the container is retained in a positive static interlocked manner without the use of resilient or elastic forces acting on the container.

Referring again to FIG. 7, it is seen from the relation of the carrier to the container that the container is held as distinguished from being gripped or resiliently retained. A space is maintained between the upper edge of the bead and the undersurface 43 of the planar frame

36 to allow relative movement between the containers and carrier. The retaining portions of the carrier are utilized to react against the container upon its movement, but by themselves, apply no resilient gripping action.

5 Thus, the carrier of the instant invention provides a more secure package by allowing a certain amount of movement of the containers. When the package is dropped, or otherwise receives an impact, there will be less probability of the carrier failing to retain the containers as contrasted with clip carriers that employ resilient grips that could release if deflected.

10 FIG. 9 shows a perspective view of a modified carrier in position on a six-pack. This carrier member 60 differs from the carrier member shown in FIG. 1-8 in that extensions or wings are provided on each end of the carrier in the form of units 62 and 63, which are one-half the basic units 28 and 30 previously described. This embodiment combines the features of carrier 14 while providing additional support for the outermost containers so

15 that each is retained at two portions of its bead instead of just the inner containers as shown in FIG. 1.

15 The container carrier of the instant invention can be fabricated as an integral unit from a resilient sheet material by molding, by an injection mold process, or other standard fabrication means. It is preferably made from a plastic material, such as high-impact styrene, due to its low cost, but any suitable material, either metallic or non-metallic, is considered within the contemplation of the invention.

20 While it will be apparent that the preferred embodiment of the invention herein disclosed is well calculated to fulfill the objects above stated, it will be appreciated that the invention is susceptible to modification, variation and change without departing from the proper scope or fair meaning of the subjoined claims.

25 What I claim is:

1. A one-piece multiple container carrier for containers having an upwardly and laterally projecting bead at the upper end of the container, said carrier having for association with each container:

- 30 (a) an upper member extending across the top of the container,
- (b) a rigid tab portion having an arcuate shaped surface integral with said upper member and depending therefrom to a location wherein said surface is symmetrically positioned in close proximity to the interior portion of the bead,
- (c) said arcuate surface having a degree of curvature that is slightly greater than the degree of curvature of said bead wherein it provides a lead-in guide for the bead,
- (d) a lower member connected in fixed spaced relation to said upper member for engaging the underside of the container bead.

2. In combination with four substantially identical cylindrical containers arranged in side-by-side substantially abutting and parallel relationship so as to provide a central space between the containers and each container having an upstanding and radically projecting peripheral bead around the top thereof, a unitary carrier for statically interlocking together the four containers, said carrier comprising:

- 35 (a) a pair of vertically spaced rigidly connected upper and lower horizontally disposed members,
- (b) said upper member in the form of a generally square shaped open frame blank extending across the top of the four containers such that each corner of the frame is positioned respectively adjacent an area of substantial abutment of the containers,
- (c) said frame having a generally square central opening the sides of which are located respectively over one container so as to define a chord of the container,
- (d) four rigid tabs extending downwardly from said upper member and having inwardly facing planar faces,

- (e) said tabs being positioned whereby said faces form respectively substantial downward continuations of the four sides of the square opening whereby the lateral extremities of each of said faces are in close proximity with the interior portion of the beading of a container,
- (f) said lower member in the form of a relatively square panel positioned in the space and having up-standing flanges integrally formed at the edges thereof, terminating in a generally upwardly facing edge for engagement with the underside of a container bead,
- (g) all portions of said carrier other than said up-standing flanges being relatively rigid and said flanges being slightly more flexible than the other portions

5

10

15

to allow the beads to be moved into their static interlocked position with said carrier.

3. A carrier as recited in claim 2, in which:

- (a) said rigid connections provide spaced stop means engageable with the exterior of each container bead, said connections disposed to limit the movement of each container to a predetermined amount.
